STRAP SEALING APPARATUS

William C. Childress, Oak Park, Ill., assignor to
Acme Steel Company, Chicago, Ill., a corpora-
tion of Illinois

Application February 13, 1935, Serial No. 6,309

16 Claims. (CL 81—9.1)

This invention relates to improvements in strap sealing apparatus and its purpose is to provide improved means for applying a metal seal to overlapping strap ends, such as those employed 5 in reinforcing boxes or packages or binding together a group of packages, and then deforming the strap and seal to provide an interlocking joint. In the co-pending application of Ralph H. Norton Serial No. 727,455, filed May 25, 1934, 10 which has now matured into United States Patent No. 2,097,955, dated November 2, 1937, there is disclosed a form of strap sealing apparatus in which a plurality of channel-shaped seals are stacked one upon the other in a magazine forming 15 a part of the apparatus and these seals are fed in succession to a position between relatively movable sealing jaws which may be moved bodily to position a seal over overlapping strap ends, after which the relative movement of the jaws 20 bends the side walls of the channel-shaped seal about the overlapping strap ends and then shears the edges of the strap and seal to provide an interlocking joint and prevent relative endwise movement of the strap ends. In that form of 25 apparatus, the means for feeding the seals from the magazine to the jaws of the sealing device is actuated by certain mechanism which performs the function of drawing the strap taut around the box or package preliminary to applying the channel-shaped seal to the overlapping 30 ends thereof.

The principal object of the present invention is to provide a modification of the apparatus disclosed in said application of Ralph H. Norton 35 wherein a magazine is provided for storing a plurality of sealing blanks which may be flat or curved or slightly bent, as distinguished from a channel-shaped form, and which are adapted to be applied to the overlapping strap ends and to be bent from their initial shapes to embrace completely the overlapping strap ends preliminary to the operation of shearing the edges of the strap and seal to cause the strap ends and the seal to interlock with each other. A further object of 40 the invention is to provide an improved form of seal of a substantially flat or slightly curved shape which is so modified as to cause it to bend along predetermined lines when it is acted upon by the apparatus of the present invention. Still 45 another object of the invention is to provide a new form of sealing apparatus having a magazine adapted to contain a stack of superimposed seals which are substantially flat or slightly curved and which are adapted to be fed automatically 50 from the magazine by the operation of mecha-

nism which draws a strap taut around a box or package, after which a sealing device to which the seals are fed from the magazine is moved to apply the seals contained therein to the overlapping strap ends, the application of the seal 5 being effected by first bending the seal to cause it to enclose the overlapping strap ends and then deforming the edges of the strap and seal as, for example, by shearing these edges and deflecting intervening portions of the metal to provide 10 interlocking or abutting shoulders. Still another object of the invention is to provide strap sealing apparatus comprising a sealing device embodying relatively movable jaws having parts which, upon relative movement of the jaws, are 15 adapted first to bend a substantially flat sealing blank about overlapping strap ends and then to shear the lateral edges of the strap and seal. Other objects relate to various features of construction and arrangement which will appear 20 more fully hereinafter.

The nature of the invention will be understood from the following specification taken with the accompanying drawings, in which one embodiment is illustrated. In the drawings, 25

Fig. 1 shows a side elevation of a box or package reenforced by surrounding metal straps and having positioned thereon the improved sealing apparatus of the present invention, which is shown in operative position with respect to the 30 overlapping ends of one of the straps;

Fig. 2 shows an enlarged front elevation of the strap sealing apparatus shown in Fig. 1;

Fig. 3 shows a perspective view of one form of a substantially flat seal, constructed according to 35 the present invention and adapted to be employed with the sealing apparatus illustrated in Figs. 1 and 2;

Fig. 4 shows a perspective view of the completed joint which is formed by the operation of 40 the sealing apparatus of the present invention;

Fig. 5 is a perspective view of the bottom of a modified form of seal which may be employed with the sealing apparatus of the present invention;

Fig. 6 is a perspective view of a third form of seal which may be employed with the sealing apparatus of the present invention;

Fig. 7 shows a horizontal section taken on the line 7—7 of Fig. 2;

Fig. 8 shows a detail vertical section taken on the line 8—8 of Fig. 7;

Fig. 9 shows a detail section taken on the line 9—9 of Fig. 7;

Fig. 10 shows a vertical section taken on the 55

line 10—10 of Fig. 7, showing the movable head of the apparatus and the sealing jaws in their elevated positions;

Fig. 11 shows a vertical section taken on the line 11—11 of Fig. 7, showing the relative positions of the parts when the head and the sealing jaws have been lowered to apply a seal to the overlapping strap ends;

Fig. 12 is a sectional view similar to that of Fig. 11, showing the relative positions of the parts after the head has been lowered and the bending jaws have been actuated to bend the seal about the overlapping strap ends;

Fig. 13 is a sectional view similar to those of Figs. 11 and 12 showing the relative positions of the parts after the shearing dies carried by the bending jaws have been actuated to shear the lateral edges of the strap and seal;

Fig. 14 shows a vertical section on the line 14—14 of Fig. 7, illustrating the magazine in which the seals are stored and from which they are fed to the relatively movable jaws of the sealing device;

Fig. 15 is a sectional view taken on the line 15—15 of Fig. 7, showing the means for causing the strap stretching mechanism to effect the operation of the means by which the seals are fed from the magazine;

Fig. 16 shows an enlarged inclined section taken on the line 16—16 of Fig. 14;

Fig. 17 shows a vertical section taken on the line 17—17 of Fig. 16;

Fig. 18 shows a section taken on the line 18—18 of Fig. 16;

Fig. 19 shows an enlarged sectional view through the lower portions of the sealing jaws, showing the relative positions of the bending dies when they have bent the lateral edges of the seal about the strap ends;

Fig. 20 shows an enlarged vertical section through the sealing jaws illustrating the relative positions of the parts when the shearing dies have been actuated to shear the lateral edges of the strap and seal and to deflect intervening portions to form an interlocking joint; and

Fig. 21 is a longitudinal section taken on the line 21—21 of Fig. 7.

As illustrated in Fig. 1, the improved strap sealing apparatus 25, embodying the features of the present invention, is illustrated in position on top of a box 26 which has applied thereto a pair of steel binding straps 27 which surround the box and which have their overlapping ends united by the use of the apparatus 25, shown in operative position with respect to one of the straps. The ends of each strap 27 are adapted to be engaged by gripping devices embodied in the tool 25 which is operated to draw the strap taut around the box. When the strap has thus been drawn taut, the apparatus is operated to cut off the strap from the source of supply and to place over the overlapping strap ends a substantially flat metal seal which is fed to the sealing device from a magazine in which a number of seals are stored. The operation of the mechanism which draws the strap taut is adapted to feed a seal from the magazine to the sealing devices which are carried by a movable head and when a seal has been inserted between these devices, the head is moved downwardly to effect the cutting off of the strap and to place the seal in a position where it may be bent to embrace the strap ends, whereupon the sealing devices are operated to bend the walls of the seal about the strap and then to shear the edges of the strap and

seal to form an interlocking joint of the type described and claimed in the United States patent of Ralph H. Norton No. 1,260,016, dated March 19, 1918, one form of which is shown in Fig. 4 of the drawings. The apparatus of the present invention is particularly adapted to be employed with a substantially flat or slightly curved seal, several forms of which are illustrated in Figs. 3, 5 and 6 of the drawings.

The seal 28, shown in Fig. 3, comprises a metal member having an intermediate flat portion 28^a which is united with side portions 28^b along parallel longitudinal bending lines 28^c about which the side portions are slightly bent with respect to the portion 28^a when the seal is initially formed. The side portions 28^b of the seal are provided, at some distance inwardly from the edges 28^d, with projections 28^e, which are adapted to engage the side portions of the next adjacent seal, when a plurality of seals are piled one upon the other to form a stack for placing in the magazine of the sealing tool. There are preferably two such projections 28^e on each side portion 28^b of each seal and these are spaced inwardly from the ends of the seal. The projections 28^e may be conveniently formed by punching the side portions 28^b at the time that these portions are initially deflected with respect to the part 28^a. The bending lines 28^c are spaced apart to agree substantially with the width of the strap to which the seal is to be applied and the initial deflection of the side portions 28^b gives the seal a tendency to bend about the lines 28^c so that it will bend along these lines when subsequently operated upon by the sealing devices 35 for bending the seal about the strap. The flat portion 28^a of each seal is provided centrally with an aperture 28^f and these apertures align with each other when they are arranged in the form of a stack so that they may be engaged by a wire, string or other fastening member for securing the seals of the stack in assembled relation while they are being transported and while they are being placed in the magazine, whereupon the fastening member is removed. A relatively soft, ductile wire is preferably employed for this purpose and the ends of the wire may be transversely bent around the ends of the bundle to maintain the seals in assembled relation, as described and claimed in the co-pending application of Chester M. MacChesney Serial No. 727,410, filed May 25, 1934, which has now matured into United States Patent No. 2,062,098, dated November 24, 1936. When the bundle of seals has been placed in the magazine of the sealing apparatus, the wire may be pulled out of the aligning apertures 28^f to release the seals for engagement by the seal feeding means which moves them successively into engagement with the sealing device of the movable head. The projections 28^e provide point to point contacts between adjacent seals which space the body portions of these seals slightly apart to facilitate the removal of the lowermost seal only from the magazine on each operation of the feeding means, in addition to reducing the frictional resistance between the lower seal and the next adjacent one during this sliding movement. Each seal employed with the sealing apparatus of the present invention is preferably formed of metal which is hard and stiff but which has a slight resiliency and sufficient ductility to cause it to retain a permanent set after the side portions 28^b have been bent around the overlapping ends of the strap.

In Fig. 5 of the drawings, there is shown an- 75

other form of seal 29 which has a flat central portion 29^a separated from parallel side portion 29^b by intervening longitudinal score lines 29^c which indent the metal for some distance inwardly from each end so that the seal has a tendency to bend along these lines when pressure is applied to the lateral edges 29^d of the seal. These score lines may be formed by indenting the metal and, at the same time that they are formed, the blank is punched to form projections 29^e which are adapted to space adjacent seals slightly apart when they are stacked upon each other, thus providing the advantages heretofore pointed out in connection with the seal 28. The center of each seal 29 is provided with an aperture 29^f and these apertures align with each other when the seals are stacked so that they may be secured together by a wire or other fastening means for convenience in transporting them or placing them in the magazine of the sealing tool.

In Fig. 6 there is shown another form of seal 30 which is in the form of a rectangular metal plate having a slight transverse curvature between its longitudinal edges 30^d. This seal is provided at its ends with pairs of oppositely disposed notches 30^c which give the seal a tendency to bend along lines extending between opposite notches so that when the seal is applied to the overlapping strap ends, the side portions 30^b tend to bend along the lines connecting the notches 30^c while the intervening portion 30^a engages one side of the strap end. As in the other forms of seal described above, the seal 30 is provided with punched projections 30^e which space the seals slightly apart and reduce the frictional resistance between them when the lowermost seal is withdrawn from the stack. The seals 30 are provided with central apertures 30^f for engagement by a wire or other fastening member when the seals are stacked upon each other.

When any of the seals 28, 29 or 30 is applied to the overlapping strap ends 27^a and 27^b by the use of the sealing apparatus of the present invention, the lateral edges of the seal are bent beneath the overlapping strap ends, as shown in Fig. 4, by the operation of the bending dies and the operation of the shearing dies operates to shear the lateral edges of the strap and seal along the lines 31 with a deflection of the metal between the shear lines to form lugs 32. In the embodiment shown in Fig. 4, there are two pairs of cuts on each side of the seal and two downwardly deflected lugs 32 which provide abutting shoulders preventing relative endwise movement of the strap ends.

The sealing apparatus 25 comprises a base plate 33 which is adapted to rest upon the surface of the box or package about which a strap 27 is to be drawn taut and sealed. This plate 33 preferably has the irregular contour shown in Fig. 7 and the forward portion thereof is provided with two pairs of relatively movable gripping devices which are adapted to grip the opposite end portions of the strap and to hold them while the strap is being drawn taut. One pair of gripping devices is carried directly by the base plate and for this purpose the forward portion of the plate 33 is provided with an upwardly extending integral block or boss 34 having an overhanging flange 34^a adapted to conform to and contact with the curved upper end of a movable gripping dog 35 which is pivotally mounted upon a pin 36 engaging the back wall of this boss, as shown particularly in Fig. 8. This gripping dog is provided on its under side with a serrated gripping

surface 35^a which is adapted to coact with the upper side of the end portion 27^a of the strap 27 when this strap is seated upon the stationary gripping plate or flange 37 which projects forwardly as an integral part of the base plate 33. This gripping plate or flange has its outer edges beveled downwardly as shown at 37^a to facilitate the insertion of the strap beneath the movable gripping dog 35 which is similarly provided with a tapered portion 35^b adapted to cooperate with the beveled surface 37^a to form a tapered passage to receive the strap, as shown in Fig. 8. The serrated surface 35^a of the gripping dog 35 is offset toward the right, as viewed in Fig. 2, with respect to a vertical plane passing through the axis of the pivot pin 36, so that when the end 27^a of the strap is inserted beneath it, a pull on the strap toward the left, as viewed in Fig. 2, will tend automatically to increase the grip of the dog 35 upon the strap. When a pull is exerted upon the strap in the opposite direction, the dog 35 tends to release its grip so that the strap may be readily removed from its position over the plate or flange 37. The gripping dog 35 is provided between its gripping surface and the pin 36 with an inwardly extending slot 35^c adapted to receive the body portion of the strap 27 after the strap has been passed around the box or package. This supply portion of the strap is adapted to be held in this slot 35^c by frictional engagement with a ball 38 which is pressed downwardly by a coil spring 39 engaging a recess in the gripping dog 35 and an aligning recess in the overhanging part of the boss 34. A threaded plug 40 adjustably engages the upper end of this spring, and this plug may be adjusted to vary the compression of the spring which, in addition to maintaining the ball 38 in contact with the supply portion of the strap 27, forces the dog 35 downwardly into engagement with the upper end portion of the strap 27 which is seated upon the plate or flange 37.

After the strap 27 has been inserted beneath the dog 35 and passed around the box or package, the other end portion 27^b thereof is placed in position to be gripped by a movable pair of gripping devices comprising a block 44 which is slidably mounted on the front portion of the base plate 33 at the end thereof opposite the block 34. This block 44 is secured by cap screws 45 to the end of a bar 46 which is slidably mounted on the base plate for movement parallel to the front edge thereof and parallel to the direction in which the strap is passed around the package. As shown in Figs. 2 and 15, the block 44 comprises an overhanging portion 44^a which is curved to conform to the curvature of the upper end of the contacting gripping dog 47, pivotally mounted upon a pin 48 secured in the rear wall of the block. The gripping dog 47 is provided on its under side with a serrated gripping surface 47^a which is adapted to coact with the upper side of the end portion 27^b of the strap when the strap is seated upon the gripping plate or flange 49 formed integrally with and projecting forwardly from the lower part of the block 44. The gripping dog 47 is inclined so that the gripping surface 47^a is offset toward the left, as viewed in Fig. 2, with respect to a vertical plane through the axis of the pin 48, so that a pull upon the strap 27 toward the right, as viewed in Fig. 2, tends to increase the grip of the dog 47 upon the strap, while a pull upon the strap in the opposite direction serves to effect the automatic release of the strap from the gripping dog. This gripping dog 47 is moved into engage-

ment with the strap by a coil spring 58 which engages a passage 51 formed in the overhanging portion of the block 44, with one end thereof engaging the inclined upper surface of the gripping dog and with the other end thereof engaging a plug 52 which threadedly engages the passage 51 to permit adjustment of the compression of the spring.

The bar 46, to which the block 44 is attached by the studs 45, is mounted to slide in a groove 56 which is formed in the upper side of the base plate 33, as shown particularly in Figs. 7, 8, 14 and 15, and it is held against upward movement by a bracket or frame 57 and a block 58, both of which are secured to the base plate 33 by screws 59 passing upwardly therethrough, so that they bridge the groove 56 in spaced relation to each other. The bracket 57 extends upwardly from the base plate and supports the seal storage magazine and the seal feeding mechanism hereinafter described. The extremity of the bar 46, opposite the block 44 is reversely bent, as shown in Fig. 21, to overlie the end of a lever 60 which is pivotally secured to the end of the bar 25 by a pin 61. The lever 60 extends rearwardly over the base plate 33, as shown in Fig. 7, and has an intermediate part thereof pivotally connected by a pin 62 with a link 63, the forward end of which is pivotally secured to the stationary block 58 by means of a pin 64 passing through the upper and lower flanges 58^a and 58^b, respectively, of this block, as shown in Fig. 21. The lever 60 is adapted to be oscillated about the pin 62 to cause it to assume the position shown by 35 dotted lines at 60^a in Fig. 7, thereby causing movement of the block 44 toward the block 34 for the purpose of drawing the strap 27 taut around the box or package. The lever 60 is reinforced on its upper side by a bar 60^b which has 40 the forward portion thereof bent upwardly to overlie the rear end of the link 63 and engage the pin 62, as shown in Fig. 10, and the rear end of the lever 60 is reversely bent to form a part 60^c which extends parallel to the body portion 45 thereof and which is adapted to receive beneath it the rear flattened end 65^a of a link 65. This link is pivotally connected to the lever 60 by a pin 66 which passes vertically through the body portion of the lever, through the reenforcing bar 60^b and through the reversely bent portion 60^c. These parts are embraced and held against upward movement by a yoke 67 which is secured 50 to the base plate 33 by screws 68 extending upwardly through the plate, as shown in Figs. 7 and 10. The forward end of the link 65 has a flange 65^b lying in a vertical plane, which engages the slot 69^a formed in a crank arm 69 which is constructed integrally with the hub 70^a of an operating lever 70 adapted to be manually manipulated to effect the stretching of the strap by causing the block 44 to move toward the block 34. The flange 65^b of the link 65 is pivotally connected to the crank arm 69 by a pin 71, and the hub 70^a of the operating lever 60 is secured by a transverse pin 72 upon a shaft 73 which is journaled in bushings 74 mounted in apertures formed in upwardly extending arms or posts 75 secured to or formed integrally with the base plate 33, as shown particularly in Fig. 7. 70 A washer 76 of leather or other friction material is secured to the side of one of the posts 75 to bear against the hub 70^a of the lever or handle 70, and a coil spring 77 is mounted on the shaft 73 to bear at one end against a collar 78 fixed on 75 the shaft and at the other end against the washer

74^a which seats against the bushing 74 adjacent to the hub 70^a, and thus hold the shaft 73 in its bearings while maintaining the hub 70^a in frictional contact with the leather washer 76. This construction is adapted to hold the lever 70 in any 5 desired adjusted position, thus maintaining a corresponding fixed spaced relation of the blocks 34 and 44 while the strap is being applied to the gripping devices. Upon movement of the lever 70 to the rear, that is, toward the left as viewed in Fig. 10, 10 the rear end of the lever 60 is moved in a forward direction and the forward portion of this lever swings outwardly about the pin 62 until the lever occupies the position shown by the dotted lines 60^a in Fig. 7. This movement of the 15 lever causes the bar 46 to slide on the base plate with a corresponding movement of the block 44 with respect to the block 34. An important advantage of this construction is that the operation of the lever 70 produces a rapid relative 20 movement of the blocks 34 and 44 during the early part of the stretching operation when the strap is comparatively slack, while the rapidity of motion decreases and the force exerted upon the strap increases as the final stages of the 25 stretching operation are approached, thus making it possible to draw a strap taut in a single operation of the lever 70.

The sealing of the overlapping ends of the strap, by the application thereto of a seal 28 (or 30, 29, or 30), is effected by a movable head 80 comprising a pair of side plates 81 which are pivotally mounted on a shaft 82 fixed in the lower parts of the posts 75, as shown in Figs. 7, 10, 11, 12 and 13. The plates 81 are notched on their 35 upper sides, as shown at 81^a, to receive the shaft 73 when the head 80 is in its uppermost position, and these plates are adapted to receive between them a pair of jaws 83 which are pivotally mounted upon pins 84 having their ends 40 secured in these plates. Each jaw member is made up of a plurality of bending dies 83^a and a plurality of cutting dies 83^b which are arranged alternately, side by side, in each jaw member as shown particularly in Figs. 11, 16 and 18. In 45 this instance, there are three bending dies and two interposed cutting dies in each jaw member. The die plates of the jaw members are provided on their inner edges with curved surfaces 83^c, concentric with the axes of the pivot pins 84, 50 and these curved surfaces are adapted to move in close proximity to each other when the jaw members are pivoted about their axes. Between these curved surfaces and below the line of their nearest proximity, there is mounted a seal supporting member or saddle 85 which is substantially triangular in cross-section, having curved surfaces 85^a which are adapted to coact with the curved surfaces 83^c of the jaw members, as shown in Figs. 19 and 20. This saddle 85 is 55 provided at each end with an integral projecting trunnion 85^b, shown in Figs. 10, 11 and 16, and these trunnions engage apertures in the side plates 81 to support the saddle in position between the jaw members which are thus capable 60 of relative angular movement without disturbing the position of the saddle.

The lower portions of the bending dies 83^a of the jaw members are provided with inwardly projecting hooks or jaws 83^d. These bending 70 dies are undercut or recessed above the hooks or jaws 83^d, as shown at 83^e, and these recesses are adapted to be engaged by the edges of the seal 28 when the seal is initially placed between the jaw members, as shown in Fig. 10. The 75

bending dies 83^a which are on the right hand side of the head 80 , as viewed in Figs. 10 and 11, extend upwardly and outwardly from the pivot pins 84 upon which they are mounted and then 5 terminate in upwardly and inwardly inclined arms 83^f which are provided on their inner ends with curved surfaces 83^g adapted to be engaged by an operating member for effecting movement of the die plates about their pivots. At the other 10 side of the head 80 , the die plates 83^a of the other jaw member 83 extend upwardly to form arms 83^h which are provided on their inner sides with surfaces 83^i adapted to be engaged by an actuating member.

15 The cutting die plates 83^b which are positioned between the bending die plates 83^a are mounted for relative movement with respect to the plates 83^a about the pivot pins 84 and they are provided at their lower ends with inclined cutting edges 83^j which, when the cutting dies of opposite jaw members are moved toward each other, are adapted to shear the lateral edges of the seal and the enclosed strap ends to form an interlocking joint of the construction illustrated in Fig. 20

25 4. The cutting die plates 83^b in the jaw member 83 at the right hand side of the head 80 , as viewed in Figs. 11, 12 and 13, extend upwardly and outwardly from the pivot pin 84 upon which they are mounted and terminate in upwardly and inwardly inclined arms 83^k , which are similar in 30 form and normal position to the arms 83^f formed on the bending dies. At the left hand side of the head 80 , as viewed in Figs. 11, 12 and 13, the cutting dies 83^b extend upwardly from the pivot pin 84 upon which they are mounted, but are relatively short and are provided at their upper ends with inclined or curved surfaces 83^m to accommodate the adjacent operating member which is provided for the purpose of effecting pivotal 35 movement of these die plates. The die plates 83^b in the other jaw member have inner surfaces 83^l formed on the arms 83^a which are also adapted to be engaged by the actuating members. For the purpose of returning the cutting die 40 plates 83^b to their normal positions with respect to the bending die plates 83^a , as shown in Figs. 10 and 11, after these cutting die plates have been moved from their normal positions, the cutting die plates 83^b are provided with pins 83^n 45 which project laterally therefrom through elongated slots 83° which are formed in the bending dies 83^a of each jaw member 83 . These pins also project through elongated curved slots 81^b which are formed in the side plates 81 and the projecting ends of these pins are provided with annular grooves which are engaged by the eyes 86^a 50 formed on the ends of the arms of loop springs 86 which are positioned on the outer sides of the side plates 81 and which are adapted normally, through their connections with the pins 83^n , to move the die plates 83^a and 83^b to their normal 55 positions shown in Fig. 11. When the die plates are in these normal positions, as shown in Fig. 10, the lower portions of the die plates are adapted 60 to receive between them the substantially flat seal 28 , the edges 28^d of which engage the recesses 83^e formed in the bending die plates 83^a . The next operation, after the seal has been 65 inserted, consists in lowering the head to position the seal 28 over the overlapping strap ends, as shown in Fig. 11. After this has been done, the bending die plates 83^a are actuated, independently of the cutting die plates 83^b , to bend the lateral portions 28^b of the seal downwardly 70 and inwardly around the overlapping strap ends, 75

as shown in Fig. 12. Following this operation, the cutting die plates 83^b are actuated to shear the lateral edges of the strap and seal and form the interlocking joint illustrated in Fig. 4.

The bending and cutting die plates of the jaw 5 members 83 are adapted to be actuated by a cam 90 which constitutes the hub of an operating lever 92 pivotally mounted upon a pin 93 which extends between and is secured in the side plates 81 . When the operating lever 92 is in its normal 10 position with respect to the side plates 81 and the jaw members 83 , as shown in Fig. 10, the lower portion 90^a of the cam 90 occupies a position between the arms 83^f and the arms 83^h of the bending dies and above this portion 90^a of the cam 15 there is a curved inclined surface 90^b formed on a projection 90^d and engaged by the surfaces 83^g of the arms 83^f , while at the other side the part 90^a has surfaces 90^c which lie in contact with the surfaces 83^l of the arms 83^h . Assuming that 20 a seal 28 is positioned between the jaw members as shown in Fig. 10, the head 80 is then lowered to the position shown in Fig. 11 to locate the seal 28 over the overlapping strap ends 27^a and 27^b , and the parts are then in readiness to cause the 25 edges of the seal 28 to be bent about the overlapping strap ends by the inward movement of the hooks or jaws 83^d which are formed on the lower ends of the bending die plates. This is accomplished by moving the operating lever 92 30 forwardly or toward the right, as viewed in Fig. 11, from the position shown in Fig. 11 to the position shown in Fig. 12. When this occurs, the surfaces 83^g of the arms 83^f of the right hand 35 jaw member 83 are engaged by the surface 90^b on the projection 90^d of the cam and are caused to move outwardly away from the pivot pin 93 while, at the same time, the surfaces 83^l of the arms 83^h of the bending dies of the other jaw 40 member 83 are forced away from the pivot pin 93 by the coaction therewith of the surface 90^c of the cam and the lower arcuate surface 90^e thereof. By the time the operating lever 92 has 45 reached the position shown in Fig. 12, the upper portions of the bending die plates of the opposite jaw members 83 will have been spread apart to their maximum extent with the result that the side portions 28^b of the seal 28 will have been bent around the overlapping strap ends to form an 50 enclosing sleeve closely embracing the overlapping portions of the strap.

After the parts have assumed the relative positions shown in Fig. 12, the operating lever 92 is moved further toward the right as viewed in that figure until it occupies the position illustrated in 55 Fig. 13. During this movement, the bending dies remain substantially stationary, but the cutting dies 83^b are then actuated by other portions of the cam 90 . The arms 83^k of the cutting dies which are embodied in the right hand jaw member 83 are actuated by the projecting portion 90^f of the cam which is located above the portion 90^e . At the same time the curved surfaces 83^m of the opposite cutting die plates are engaged by a projection 90^f formed on the lower part of the cam which is adapted to force these die plates outwardly about their pivots. As a result of this action, the opposed cutting die plates are caused 60 to move about their pivots with the result that the cutting edges 83^j formed on their lower ends are adapted to shear the lateral edges of the strap and seal and then to deflect the intervening portions of the metal to provide the projecting lugs 32 and abutting shoulders shown in Fig. 4. When 65 this operation has been completed, the operating 70 lever 92 is moved back to the position shown in Fig. 12. The seal 28 is then lowered to the position shown in Fig. 11, the bending die plates 83^a are actuated, and the cutting die plates 83^b are actuated to shear the lateral edges of the strap and seal and then to deflect the intervening portions of the metal to provide the projecting lugs 32 and abutting shoulders shown in Fig. 4. When 75 this operation has been completed, the operating lever 92 is moved back to the position shown in Fig. 12.

lever 92 is moved in the opposite direction about its pivot 93 with the result that both the cutting die plates and bending die plates are restored to their normal positions by the action of the springs 86 which act upon the pins 83^a while these pins in turn act upon the ends of the slots formed in the bending die plates.

The jaw member 83 which is positioned nearer to the pivotal axis 82 of the head 80 is connected to the pin 82 by a pair of links 96 and 97. The link 96 is pivotally connected to the jaw member by a pin 98 and it is pivotally connected at its other end to the link 97 by means of a pin 99. The lower end of the link 97 is pivoted on the pin 82 which has sleeves 100 mounted thereon for spacing the links midway between the side plates 81. The link 96 projects into a slot 97^a formed in the end of the link 97 and this end of the link 96 is rounded on the lower corner thereof as shown at 98^a, to permit relative angular movement of the two links in an upward direction only, relative angular movement in a downward direction being prevented beyond the point where the two links are in substantial alignment with each other, because of the engagement of the angular upper corner of the link 96 with the end wall of the slot 97^a formed in the other link. When the two links 96 and 97 are thus in alignment, the axis of the pin 99 is located below or to the right of a plane containing the axes of the pins 82 and 98, so that the two links which act as a toggle connection between the jaw members 83 and the pivotal axis of the head 80, thereby preventing relative movement of the jaw members while the links occupy these aligning positions. This toggle connection permits the head 80 to be moved downwardly by the jaw members 83 with the lever 92 in the upright position shown in Fig. 10, until the seal 28 held between the jaw members 83 has been passed into position over the overlapping strap ends, as shown in Fig. 11. As the head 80 approaches the position shown in Fig. 11, a stop member 101, threadedly engaging the link 97, abuts against the base plate 33 with the result that the link 97 is held against further movement and the toggle connection between the two links is then broken upon continued downward movement of the head 80. This breaking of the toggle connection allows the operating lever 92 to be then moved in a forward direction from the position shown in Fig. 11. This movement of the lever 92 about its pivot 93 causes the cam 90 to actuate the bending die plates 83^a to bend the lateral portions of the seal about the overlapping strap ends, as shown in Fig. 12, and the further movement of the lever 92 in the same direction results in the shearing of the lateral edges of the strap and seal by the cutting die plates 83^b, as shown in Fig. 13. A nut 102 threadedly engages the stop member 101 and holds it in adjusted position. By adjusting the position of the stop member 101 it may be caused to break the toggle joint at the desired point in the movement of the head 80.

The flange 37 of the base plate 33 extends transversely of the base plate for a considerable distance, as shown in Figs. 2 and 7, and it underlies the forward portion of the block 58 which is secured upon the base plate as previously described. The base plate has another forwardly projecting flange 107 which extends outwardly parallel to the flange 37 and spaced therefrom so that an inwardly projecting notch or opening 108 is formed between these flanges in registry with the path of movement of the jaws

83 as the head 80 is lowered, thus permitting the jaw members to be closed about the seal and strap in this notch or opening 108 while the strap is supported on the adjacent flanges 37 and 107. The flange 107 is beveled on its upper side at its forward edge, as shown at 107^a to correspond with the bevel on the forward edge of the flange 37, to permit the convenient insertion of the strap. At the commencement of the operation of applying a strap 27 around a box or package, the free end 27^a of the strap is first inserted between the gripping dog 35 and the flange 37 with the extremity of the strap projecting across the opening 108 and resting upon the flange 107, as shown in Fig. 2. The strap is then passed around the box or package and the portion 27^b thereof, which is connected to the source of supply, is passed beneath the gripping dog 47 so that it is held against the flange 49 carried by the movable block 44. After being passed beneath the gripping dog 47, the supply portion 27^b of the strap is placed in position over the extremity of the free end 27^a of the strap on the flange 107, as shown in Fig. 2, and beneath the forward end of the overlying portion of the bracket 57 by which the seal storage and feeding mechanism is carried. The strap is then inclined upwardly toward the left, as viewed in Fig. 2, and passed over a stationary cutting die 110, from which point the supply portion of the strap is carried over the flange 37 of the base plate and caused to occupy the slot 35^c in the gripping dog 35. The stationary cutting die 110 has the form shown particularly in Fig. 10, being provided with two oppositely extending blades 110^a, each of which has a cutting edge 110^b. At its middle point, the die has an upwardly extending lug 110^c which is apertured for engagement by a bolt 111 by which it is secured to the flange 58^c formed on the block 58. When thus secured in place by the bolt 111, the lower edge of the die 110 rests upon the upper surface of the base plate 33 so that angular movement thereof is prevented. The under portions of the blades of the cutting die 110 are inclined upwardly as shown at 110^d in Fig. 10 to facilitate the insertion beneath the cutting blade of the free end portion 27^a of the strap.

The stationary cutting die 110 is adapted to cooperate with a cutting blade 112 mounted upon a shearing lever 113 which is pivotally supported on the bolt 111 and which is connected with one end of a link 114 having its other end pivotally connected to a pin 114^a stationarily mounted upon the adjacent side plate 81 of the head 80. The pin 114^b which connects the lever 113 with the link 114 has a coil spring 119 connected thereto and this spring is attached at its other end to a stationary pin 119^a carried by the base plate 33. This spring 119 tends normally to rock the shearing lever 113 about its pivot 111 in a direction to elevate the cutting blade 112. The action of this spring 119 tends also to elevate the head 80 about the pin 82 since it tends to move the pin 114^b toward the pin 119^a, as viewed in Fig. 10. The extent of this movement is limited by the engagement of one of the side plates 81 of the head with a flange 103^a formed on an adjustable stop arm 103 which is pivoted on one of the bushings 74 carried by the shaft 73, as shown in Figs. 7, 11 and 12. This stop arm is provided at its lower end with a horizontal flange 103^b which rests upon the head of a screw 104 adjustably engaging the base 33, being held in engagement with that screw by

another screw 105 which passes through the flange and also enters a threaded aperture in the base. As the head 80 is lowered by forward pressure on the lever 92, the first effect of the downward movement of the head is to lower the shearing lever 113 against the action of the spring 119 until the shearing blade finally engages the upper supply portion of the strap 27 and shears it off by cooperating with the underlying cutting die 110. Immediately after the strap is cut off from the source of supply by the action of the blades 110 and 112, the seal 28 carried between the jaw members 83 engages the upper end portion of the strap which has just been cut off from the source of supply and forces it downwardly against the underlying end portion 27a. As soon as this has occurred, or immediately before it occurs, the previously adjusted stop member 101 engages the base plate 33 to break the toggle connection formed by the links 96 and 97 so that these links then move upwardly as viewed in Figs. 10 and 11, and the lever 92 is then permitted to move forwardly about its pivot 93 with the result that the jaw members 83 are actuated as heretofore described to effect first the bending of the side portions of the seal about the strap, as shown in Fig. 12, and then the shearing of the lateral edges of the strap and seal, as shown in Fig. 13. When these operations have been completed the joint shown in Fig. 4 is formed and the lever 92 is then moved toward the left, as viewed in Fig. 13, thereby releasing the lower parts of the jaws from engagement with the strap and seal due to the turning of the cam 90 about the pin 93 and the separation of the lower portions of the jaw members 83 under the influence of the springs 86. The continued movement of the lever 92 in the same direction then results in the upward 40 tilting of the head 80 about its pivot 82 and a corresponding elevation of the shearing lever 113, until these parts assume their normal upper positions shown in Fig. 10, in which position the parts are held by the spring 119. This upper position of the head 80 may be varied by adjusting the plate 103 to vary the position of the flange 103a which is engaged by one of the side plates 81 when the head is in its upper position. The operator then reverses the motion of the stretching lever 70 with the result that the block 44 is moved toward the right, as viewed in Fig. 7, thereby releasing the sealed strap from the grip of the dog 47. The tool may then be moved bodily toward the left, as viewed in Fig. 2 and away from the strap to release the strap from the gripping dog 35. As this is done, the flanges 37 and 107 are withdrawn from their positions beneath the strap and the strap is then permitted to snap downwardly into contact with the top surface of the box or package.

When the lever 92 is elevated with the head 80, it should be turned angularly about its pivot 93 until it is restored to the normal position shown in Fig. 10, thus permitting the lower 65 seal-engaging portions of the jaw members 83 to be separated to their maximum extent under the influence of the springs 86. To insure this turning of the lever 92 about the pivot 93 to the normal initial position shown in Fig. 10, a 70 coil spring 108 is mounted on the enlarged portion 93a of the pivot pin 93 between the head 93b of the pin and the adjacent side plate 81, as shown in Figs. 2 and 10, and the ends of this spring are so arranged that the spring causes 75 the turning of the pin 93 and of the lever 92

mounted thereon, toward the left as viewed in Fig. 10, when the lever is released by the operator. For this purpose, one end 108a of the spring bears against the pin 114a which connects the link 114 with the adjacent side plate 81 and the other end 108b of the spring is secured to a pin 109 which is fixed on the lever 92, so that the spring is coiled and put under tension by the turning of the lever 92 toward the right from the position illustrated in Fig. 10.

The seal storage and feeding mechanism which introduces the seal 28 into the space between the lower portions of the jaw members 83 is carried by the previously described bracket 57 which is attached to the base plate 43 by screws 59, 15 as shown in Fig. 14, and which comprises the block 57a extending over the sliding bar 46 and having an upwardly beveled front end to permit the convenient insertion of the strap. This bracket extends upwardly at one side of the 20 movable head 80 and is provided with an inclined flange 57b to which there is secured the seal magazine 115 by means of screws 116. A longitudinal rib on the magazine seats in a groove 57d formed in the flange, as shown in Fig. 7. 25 This magazine occupies an inclined position at right angles to the inclination of the head 80 when the head 80 is in its uppermost position, as shown in Figs. 14 and 15, and the magazine is provided along its front face with a longitudinal slot 115a through which access may be had to the stack of seals in the magazine. These flanges 115b at the sides of the slot engage the end portions of those side walls of the seals which are directed toward the front of the apparatus and retain the seals in place in the channel of the magazine. The lower end of the magazine rests upon a guide plate 117 which is secured to the flange 57c of the bracket by means of rivets 118, shown in Fig. 2, the guide plates 40 having flanges 117a which extend downwardly at the sides of the bracket as shown in Fig. 16. The lowermost seal 28 of the stack of seals in the magazine rests upon this guide plate 117 and is adapted to be moved over it as it is pushed endwise into the space between the portions 83e of the jaw members. If the seals be of the form shown in Figs. 3 and 6, the edges only of the lowermost seal will rest upon the plate 117, but if the seals be of the form shown in Fig. 5, they 50 will rest upon the plate 117 substantially throughout their width as they are transferred successfully over this plate to a position between the jaws. During this movement from the magazine to the jaws, the seals pass through an opening 115c which is formed in one side wall of the magazine adjacent the head 80, as shown in Fig. 16. The movement of a seal 28 through the opening 115c is effected by the movement of a reciprocating plunger or feeding member 55 60 65 70 75 80 85 90 95 100 105 110 115 120 125 130 135 140 145 150 155 portion of the next adjacent seal during the movement of the lowermost seal from the magazine to a position between the jaw members. This is permitted by reason of the fact that the body portions of adjacent seals are spaced slightly apart by the projections 28^e in the case of the seals 28, and by the corresponding projections 29^e and 30^e formed on the seals 29 and 30, respectively. During the movement of the lowermost seal from the magazine, the tooth 120^b on the plunger maintains this seal in engagement with the guide plate and at the same time it assists in separating this lowermost seal of the stack from the next seal above it. Owing to the point to point contact between adjacent seals, due to the projections formed on them, the frictional resistance which must be overcome in moving the seals from the magazine is comparatively slight. In order to insure the location of the jaw members in a position in which the seal moved from the magazine will pass into engagement with the portions 83^e of the jaw members, the stop member 103 may be adjusted by manipulating the screws 104 and 105 in order to adjust the location of the flange 103^a which determines the upper position of the head 80 under the influence of the spring 119. When a seal has just been inserted between the jaw members by the movement of the plunger 120, the parts are in readiness for the downward movement of the head 80 to position the seal over the overlapping strap ends and the subsequent relative movement of the jaw members to bend the seal about the strap ends and then deform the strap and seal to provide an interlocking joint.

The plunger or feeding member 120 is mounted to slide in a guideway 121^a formed in a cylindrical guide member 121 constructed as a part of the bracket 57, as shown in Figs. 2 and 15. The plunger 120 is adapted to be actuated by a lever 123 provided at its rear end with an elongated slot 123^a engaged by a pivot pin 124 which is mounted in two ears 57^e formed on the bracket 57. The forward end of the lever 123 enters a slot 120^c formed in the plunger 120 and is pivotally connected to the plunger by a vertical pin 125. The forward end of the lever 123 also engages a slot 121^b in the end of the guide member 121 and the lever 123 is adapted to coat with the shoulder 121^c at the inner end of this slot to limit the seal feeding movement of the plunger at the point where it has positioned the seal properly between the jaw members 83. In addition, the outer side plate 81 has a lug or stop 81^c shown in Fig. 16 which projects into the path of the seal to engage the end of the seal and thereby position it between the jaws. The outer end of the channel 121^a in the guide member is closed by a screw threaded plug 126 which is secured in place by a spring clip 127 engaging an annular groove in the guide member and having an arm 127^a extending transversely through a hole in the guide member and engaging the end of the plug. This plug limits the outward movement of the plunger 120 away from the head 80.

The plunger 120 is normally withdrawn to its outer position, as shown in Figs. 2 and 7, wherein its outer end lies in close proximity to the plug 126, by means of a spring actuated pin 128 which is mounted in a tubular bore 129 formed in the bracket 57 with the outer end of the pin engaging the inner vertical face of the lever 123, as shown in Fig. 7. The pin 128 has an enlarged head 128^a which is slidably mounted in

the enlarged portion 129^a of the bore formed in the bracket, and a coil spring 130 is mounted between the head of the pin and a plug 131 which threadedly engages the inner end of the bore. The pin 128 thus engages the lever 123 with a resilient pressure which is adapted to withdraw the plunger 120 after it has been moved toward the left as viewed in Figs. 2 and 7 to feed a seal to a position between the jaws.

The seal feeding movement of the plunger 120 is adapted to be effected by the movement of the sliding bar 46 during the operation of drawing the strap taut around the package, so that when the strap has been drawn taut with its ends overlapping, a seal will have been placed in position 15 between the jaw members 83 in readiness for the lowering of the head 80 to cut off the supply portion of the strap and to apply the seal to the overlapping strap ends. For this purpose, a socket member 135 is secured to the block 44 by the screws 45 which have heretofore been described as securing the block to the sliding bar 46, as shown in Fig. 15. This socket member has an upwardly extending cylindrical portion provided with a bore 135^a extending upwardly from 25 the lower end thereof and this bore is occupied by an actuating member 136 having a head 136^a which projects through an opening 135^b formed in the socket member at the upper end of the bore. The tapered upper extremity of this head 30 136^a is adapted to coat with the lever 123 by which the plunger 120 is moved. The actuating member 136 has a collar 136^b which slides within the bore 135^a, and a coil spring 137 is interposed between this collar and a plug 138 which thread- 35 edly engages the lower end of the bore 135 so that the spring normally maintains the actuating member 136 in its uppermost position shown in Fig. 15. The plug 138 is apertured and is slidably engaged by the stem of the actuating 40 member.

When the lever 123 is being actuated to move the plunger 120 to feed a seal, the tapered head 136^a of the actuating member coats with the inclined surface 123^c formed on the side of the lever 45 123, as shown in Figs. 7 and 9, and, in case the operation of stretching the strap taut requires a greater movement of the sliding bar 46 than is necessary to feed the seal 28 to a position between the jaw members, the stopping of the plunger 120 by the engagement of the lever 123 with the shoulder 121^c on the guide member will prevent further movement of the lever 123 and the continued motion of the bar 46 will then cause the tapered head of the actuating member 136 to ride downwardly on the inclined surface 123^c of the lever until the actuating member is permitted to snap beneath and pass the lever 123. Then, when the stretching of the strap has been completed, and the bar 46 returns to its normal position, the tapered head of the actuating member 136 will engage the inclined surface 123^b formed on the underside of the lever 123 and the actuating member will again move downwardly against the compression of the spring 55 137 until it snaps beneath the lever 123 as the bar 46 and the block 44 are restored to their normal positions. The surface 123^b has a lesser inclination to the horizontal than the surface 123^c on the lever 123 so that while the engagement of the actuating member with the surface 123^c is adapted to effect movement of the lever 123 up to the point where a predetermined resistance is encountered, the slope of the surface 123^b is such that the actuating member 136 will 60 70 75 80 85 90 95 98 99 100

be wedged downwardly by this surface and pass beneath the lever merely by the normal return motion of the bar 46.

Each time that the stretching lever 70 is operated to draw a strap taut around a package, the lever 123 is simultaneously operated by the action of the bar 46 to cause a seal to be projected from the bottom of the magazine 115 into the space between the lower portions of the jaw members 83. Thus, when the stretching operation has been completed, the parts are in readiness for the downward movement of the head 80 which is effected by imparting motion thereto through the lever 92 with the result that as the head 80 is lowered, the supply portion of the strap is cut off from the source of supply by the action of the shearing lever 113 and the seal positioned between the jaw members is then positioned over the overlapping strap ends. Then, the forward motion of the lever 92 bends the seal along the preformed bending lines described above in connection with the forms of seal shown in Figs. 3, 5 and 6 with the result that the seal is first bent around the overlapping strap ends and is then sheared along with the enclosed strap ends at its edges to provide an interlocking joint. Successive operations of this character may be repeated very rapidly with successive substantially flat seals being fed from the bottom of the stack 30 of seals in the magazine into position between the lower portions of the jaw members 83 while the head 80 is in its uppermost position. Due to the spacing apart of adjacent seals by the projections formed thereon and the extension of the tooth 120^b on the plunger between adjacent seals, the feeding operation takes place with the projection of only one seal from the magazine at a time.

Although one form of the invention has been shown and described by way of illustration, it will be understood that it may be constructed in various other embodiments coming within the scope of the appended claims.

I claim:

1. The combination in strap sealing apparatus, of means for holding a strap with its ends overlapping, means for holding a substantially flat seal, means for moving said last named means to position said seal on said overlapping strap ends, means for bending said seal from the flat condition into tubular form enclosing said overlapping strap ends, and means associated with and operative after the operation of said last named means for deforming the strap and seal 55 to provide an interlocking joint.

2. The combination in strap sealing apparatus, of means for holding a strap with its ends overlapping, a pair of relatively movable jaw members each having relatively movable parts, means 60 for feeding a substantially flat seal to a position between said jaw members which have means for engaging and holding the edges of the seal, means for moving said jaw members bodily to position said seal over said strap ends, and means 65 for thereafter actuating said jaw members to effect relative movement of said parts and thereby to bend said seal about said strap ends and then to deform the seal and strap ends.

3. The combination in strap sealing apparatus, 70 of a jaw comprising a bending die and a relatively movable cutting die adapted to engage a strap seal.

4. The combination in strap sealing apparatus, 75 of a pair of jaws comprising bending dies adapted to engage opposite edges of a substantially flat

seal plate, each of said jaws comprising cutting dies movable relatively to said bending dies, and means for moving said dies into successive engagement with a strap seal.

5. The combination in strap sealing apparatus, 5 of a jaw member made up of a plurality of bending dies and a plurality of alternately arranged cutting dies, and means for moving said bending dies and for moving said cutting dies relatively to said bending dies.

6. The combination in strap sealing apparatus, 10 of separate means for holding a strap with its ends overlapping between said holding means, means for effecting relative movement of said holding means for drawing the strap taut around 15 a package, a movable head, a pair of relatively movable jaw members carried by said head, each of said jaw members comprising relatively movable bending and cutting dies, said bending dies of opposite jaw members being adapted to hold 20 a substantially flat seal between them by engagement with the edges of the seal, means for moving said head to position said seal over said overlapping strap ends, and means for thereafter operating said bending dies to bend said seal from 25 its flat condition about said strap ends while said seal is seated on said strap ends and to operate said cutting dies relatively to said bending dies to shear the lateral edges of said seal and strap ends.

7. The combination in strap sealing apparatus, 30 of a base plate, means mounted on said base plate for holding a strap with its ends overlapping, a movable head mounted on said base plate, a pair of relatively movable jaws carried by said head, 35 each of said jaws comprising a bending die and a relatively movable cutting die, said bending dies of opposite jaw members being adapted to hold a substantially flat seal between them by engagement with its opposite edges, means for moving 40 said head to position said seal over said strap ends, means for effecting relative movement of the bending dies of opposite jaw members to bend said seal from its flat condition into tubular form about said strap ends while the seal is seated on 45 said strap ends, and means for effecting relative movement of said cutting dies with respect to each other and with respect to said bending dies to deform the lateral edges of the strap and seal.

8. The combination in strap sealing apparatus, 50 of means for holding a strap with its ends overlapping, a movable head, a pair of relatively movable jaws carried by said head, each of said jaws comprising a bending die and a relatively movable cutting die, said bending dies of opposite 55 jaw members being adapted to hold a substantially flat seal between them by engagement with its opposite edges, means for moving said head to position said seal over said strap ends, means for effecting relative movement of the bending dies of opposite jaw members to bend said seal about said strap ends while said seal is seated on said strap ends, means for effecting relative movement of said cutting dies with respect to each other and with respect to said bending dies to deform the lateral edges of the strap and seal, and means for thereafter restoring said bending 60 and cutting dies to their initial relative positions.

9. The combination in strap sealing apparatus, 65 of a base plate, a movable head mounted on said base plate, said head comprising relatively movable oppositely disposed bending jaws adapted to engage opposite edge portions of a substantially flat seal and having a sufficient range of movement to bend a substantially flat seal about 70

75

overlapping strap ends, said head also comprising cutting dies which are movable relatively to said bending jaws, means for effecting relative movement of said bending jaws, and means for independently moving said cutting dies with respect to each other and with respect to said bending jaws.

10. The combination in strap sealing apparatus, of means for holding a strap with its ends overlapping, a sealing device movable toward and from said strap ends and occupying normally a position removed from said strap ends, a magazine for storing substantially flat seals, means for moving the lowermost seal from the magazine into said sealing device, said sealing device comprising relatively movable bending dies and shearing dies with respect to which said bending dies have relative movement, means for moving said sealing device bodily to position the seal 20 therein on said overlapping strap ends, and means for actuating said bending dies to bend said seal from a substantially flat condition to tubular form enclosing said strap ends and for actuating said shearing dies thereafter to deform 25 the seal and the enclosed strap ends.

11. The combination in strap sealing apparatus, of means for holding a strap with its ends overlapping, a sealing device movable toward and from said strap ends and occupying normally a 30 position removed from said strap ends, said sealing device comprising relatively movable bending jaws and deforming dies with respect to which said bending jaws are relatively movable, means for feeding a substantially flat seal into said sealing device between said bending jaws when said sealing device is in said normal position, means for moving said sealing device to position said seal on said overlapping strap ends, and means for operating said bending jaws to bend said seal 40 from its flat condition into tubular form enclosing said overlapping strap ends and for thereafter operating said deforming dies to deform the lateral edges of the seal and the enclosed strap ends to provide an interlocking joint.

45. 12. The combination in strap sealing apparatus, of means for holding a strap with its ends overlapping, a sealing device movable toward and from said strap ends and occupying normally a position removed from said strap ends, a magazine for storing substantially flat seals, means for moving the lowermost seal from the magazine into said sealing device, said sealing device comprising relatively movable bending dies and shearing dies with respect to which said bending dies have relative movement, means comprising 50 an operating lever for moving said sealing device bodily to position said seal on said overlapping strap ends, and means actuated by the continued motion of said lever for operating said bending dies to bend said seal from said substantially flat condition to tubular form enclosing said strap ends and for moving said shearing dies thereafter with respect to said bending dies to deform said seal and the enclosed strap ends.

60. 13. The combination in strap sealing apparatus, of means for holding a strap with its ends overlapping, a sealing device movable toward and from said strap ends and occupying normally a position removed from said strap ends, a maga-

zine for storing substantially flat seals, means for moving the lowermost seal from the magazine into said sealing device, said sealing device comprising relatively movable bending dies and shearing dies with respect to which said bending dies have relative movement, said bending dies being spaced to provide openings through which said shearing dies are movable, said sealing device being movable to position a seal in engagement with said overlapping strap ends, said bending dies having sufficient range of movement to bend a substantially flat seal from its flat condition into tubular form enclosing said strap ends, and means including a common operating member for moving said sealing device for positioning said seal on said overlapping strap ends and then operating said bending dies to bend said seal about said strap ends and then actuating said shearing dies to deform said seal and the enclosed strap ends.

14. The combination in strap sealing apparatus, of a base plate adapted to rest upon the surface of a package, means carried by said base plate for holding a strap taut around the package with its ends overlapping, a sealing device 25 mounted on said base plate for movement toward and from said overlapping strap ends, said sealing device normally occupying a position removed from said strap ends, a seal storage magazine carried by said base plate for storing a stack 30 of superimposed and substantially flat seals, means for moving the lowermost seal from the magazine into said sealing device, said sealing device comprising oppositely disposed bending jaws for engaging opposite edges of said seal and bending said seal from its flat condition into tubular form enclosing said strap ends, said sealing device also comprising shearing dies capable of relative movement with respect to said bending jaws, and means for actuating said bending 40 jaws to bend the seal about said strap ends and for then actuating said shearing dies with respect to said bending jaws to deform the seal and the enclosed strap ends.

15. The combination in strap sealing apparatus, of means for holding a strap with its ends overlapping, a sealing device comprising opposite relatively movable bending jaws and deforming dies which are movable relatively to said bending jaws, means for actuating said bending jaws for bending a seal to cause said seal to enclose said overlapping strap ends, and means including cams for thereafter moving said deforming dies with respect to said bending jaws to deform said seal and strap ends and thereby provide 55 an interlocking joint.

16. The combination in strap sealing apparatus, of means for holding a strap with its ends overlapping, a sealing device comprising opposite relatively movable bending jaws and deforming dies which are movable relatively to said bending jaws, an operating lever, cams actuated by said lever for moving said bending jaws to bend a seal about overlapping strap ends, and cams actuated by said lever for moving said deforming dies to deform said seal and the inclosed strap ends and thereby provide an interlocking joint.

WILLIAM C. CHILDRESS.
